UNITED STATES PATENT OFFICE.

THOMAS PEACOCK ANTHONY, OF EDGEWATER PARK, NEW JERSEY, ASSIGNOR TO
UNITED STATES CAST IRON PIPE & FOUNDRY COMPANY, OF BURLINGTON, NEW
JERSEY, A CORPORATION OF NEW JERSEY.

ANNEALING FURNACE.

Original application filed February 21, 1922, Serial No. 538,238. Divided and this application filed
May 3, 1923. Serial No. 636,494.

To all whom it may concern:

Be it known that I, THOMAS PEACOCK ANTHONY, a citizen of the United States, residing at Edgewater Park, in the county of Burlington and State of New Jersey, have invented a certain new and useful Improvement in Annealing Furnaces, whereof the following is a specification, reference being had to the accompanying drawings.

10 As hereinafter described, my invention may be advantageously employed for annealing pipes which have been manufactured by what are known as "centrifugal" processes and this application is, in part, a 15 division of my application Serial 538,238, Filed February 21, 1922 for Letters Patent of the United States, wherein such a process of centrifugally casting pipe is claimed.

In such processes, a cylindrical mold is 20 rotated while molten iron is poured therein, so that the socalled centrifugal force which rotation develops in a revolving mass, compels the molten iron to distribute itself in a cylindrical tubular shell of uniform thickness on the inside of the rotating mold. Ordinarily, such molds are water-cooled upon their exterior, with the result that the iron cast therein is chilled upon its outer surface to a depth of approximately one-thirty- 25 second of an inch; necessitating a subsequent annealing process to soften the surface of the pipe which is thus hardened.

Such hardness of the outer surface of chilled castings is due to the fact that the 30 quicker solidification incident to the rapid cooling of the metal coming in contact with the chilled mold aforesaid, causes the retention of much combined carbon and thus prevents the formation of graphite in the portions of the castings thus chilled. The purpose and effect of the annealing herein contemplated are to convert the hard brittle cementite into particles of soft graphitic carbon and, incidentally, to eliminate some 35 of the carbon in combination with such oxygen as may reach it. However, the principal object or effect of the furnace and process herein contemplated is the graphitizing of the cementite at a temperature above the critical point $Ac3.2.1$ of the cast iron and, of course, below its temperature of solidification. In order to effect such annealing at a desirably rap'd rate; it is necessary to subject the pipes to temperatures so nearly

approaching the solidification temperature 55 of cast iron that the pipes might sag, of their own weight, and thus become distorted by the mere gravitation of their mass if allowed to remain in one position during the time required for the annealing process. 60 Therefore, an essential feature of the furnace herein claimed is the means for turning the pipes upon their axes while they are subjected to such temperatures.

As hereinafter described; an essential element of the means for thus turning the pipes under treatment, are rollers upon which the pipes rest and which are notched at one portion of their peripheries, so that as the rollers are rotated, on axes parallel with the 70 axis of the pipe, they alternately turn the pipe and progress it transversely from one pair of such notched rollers to another in a series extending from one end of the furnace to the other.

As hereinafter described, my invention includes means for supporting and turning such a series of rollers upon a truck frame provided with supporting wheels, which frame is normally stationary in the furnace 80 but may be withdrawn, upon its supporting wheels aforesaid, when it is desired to afford access to the roller driving mechanism which is carried by said truck.

My invention includes the various novel 85 features of construction and arrangement hereinafter more definitely specified.

In said drawings: Fig. I is a longitudinal sectional view of an annealing furnace conveniently embodying my invention, taken on the line I, I in Fig. II.

Fig. II is a transverse sectional view of said furnace, taken on the line II, II in Fig. I.

Fig. III is a fragmentary vertical sectional view; the right hand end thereof being similar to the right hand end of Fig. I, but on a larger scale, and the left hand end thereof being taken on the section line III, III in Fig. V.

Fig. IV is an elevation of the right hand end of said truck shown in Figs. I and III, with a fragmentary section of the portion of the furnace adapted to support said truck.

Fig. V is a transverse sectional view of said truck and parts of the furnace indicated in Fig. IV, taken on the line V, V in Fig. III.

Fig. VI is a fragmentary longitudinal sectional view of said truck; the left hand portion thereof being taken on the line VI, VI in Fig. V, and the right hand portion thereof being taken on the line VI', VI' in Fig. V.

Fig. VII is a fragmentary transverse sectional view of said truck, taken on the line VII in Fig. VI.

10 Fig. VIII is a fragmentary plan view of one of the roller shaft bearings shown in section in Fig. VII.

15 Fig. IX is a fragmentary view of a part of Fig. I, on a larger scale, showing the operative relation of said rollers with the pipes under treatment.

In said figures; the furnace includes the base pit 1, extending longitudinally between the rail ledges 2, 2, upon which are mounted 20 the truck rails 3, 3 with sealing gutters 5, 5 at opposite sides thereof, formed in the foundations 6. Said foundations may be conveniently formed of concrete with air inlet passageways 7 extending beneath the 25 floor 8, and support the side walls 9 and front and rear walls 10 and 11. Said walls 9 include air flues 12 beneath the hearths 13. Longitudinal series of twyers 14 extend upon opposite sides of said furnace, in the 30 region of the combustion chamber 15, through which blasts of hot products of combustion of oil or gas may be directed above said hearths 13; such blasts being deflected upwardly by the baffle walls 16 beneath the overhanging arch 18. Said products of combustion pass from the chamber 15 beneath the overhanging bridge wall 19 into the flue chamber 20 from which they escape through flue vents 21.

40 Said front wall 10 has the opening 23 through which pipes 24, in an unannealed state, and preferably retaining the heat incident to the operation of casting them, are introduced to said combustion chamber 15, 45 and said rear wall 11 has the opening 25 through which the pipes 24 are discharged, in an annealed state. I find it convenient to confine the heated atmosphere within said furnace by the chain curtains 26 and 27 50 which are respectively pendent over said openings 23 and 25.

The essential feature of my improved mechanism for progressing said pipes 24 through said furnace is the longitudinal 55 series of rollers 29 and 30. Said rollers 29 and 30 are thus differently marked because of their location in respectively different vertical planes, as indicated in Fig. V, to permit them to be overlapped, as indicated 60 in Fig. I, but are all the same shape, which is best shown in Fig. III, each having a peripheral recess 31 which merges into the circular circumference of the roller toward the right with a gradual curve, but forms a crest 32 at 65 its junction with said circumference at the

left. The effect of such construction and arrangement is that when said rollers are turned clockwise, as indicated by the arrows in Figs. I and III, they merely turn said pipes 24 upon the respective pipe axes, in the 70 opposite direction, without progressing the pipes through the furnace, during the traverse of the circular circumference of said rollers beneath the respective pipes but, when, by such turning movement of said 75 rollers, the pipes are lowered into said recesses 31, they are caught by said crests and shifted to the right in Figs. I and III as said rollers continue to turn beneath the pipes; the movement thus effected being 80 from one roller to the next in the series extending toward the right in said figures.

However, it is to be understood that said pipes may be rotated upon their own axes, for any desired length of time, without thus 85 progressing them, by merely reversing the direction of rotation of said rollers 29 and 30 during the time it is desired to thus detain said pipes. However, if the speed of rotation of said rollers is properly calibrated 90 with reference to the temperature of the incoming and outgoing pipes; said rollers may be continuously turned clockwise with the effect of progressing the pipes step by step at each revolution of said rollers.

95 The above described movements of said rollers may be effected by any suitable means. However, I prefer to mount pairs of said rollers 29 upon respective shafts 34 and pairs of said rollers 30 upon respective 100 shafts 35, and to provide each of said shafts with a central worm gear 36, as best shown in Fig. V. Said gears 36 are respectively engaged with worms 37, as indicated in 105 Figs. V and VI, carried by the common worm shaft 38 which has the worm gear 40 rigidly connected therewith at its rear end within the housing 41. Said worm gear 40 is engaged by the worm 42 on the driving 110 shaft 43, having the gear 45, as shown in Fig. IV, engaged by the pinion 46 which may be rotated by any suitable motor. It is to be understood that the construction and arrangement above described are such 115 that when said motor pinion 46 is rotated, all of said rollers 29 and 30 are rotated, as above contemplated, and said motor pinion 46 may be rotated in either direction, to rotate said rollers 29 and 30 in either direction; suitable means being provided 120 to control the direction and rate of such rotation.

125 Although the mechanism for driving the rollers 29 and 30 as above described may be permanently mounted in the furnace inclosure; I prefer to mount it in a truck 48 which is removable with respect to said inclosure, upon supporting wheels 49, of which there are four pairs resting upon said tracks 3, as indicated in Figs. I and II; said wheels 130

being provided with independent axles 50 journaled in the longitudinal frames 51 of said truck, as best shown in Fig. V. Said longitudinal frames 51 are rigidly connected 5 by the transverse frames 52, which also support intermediate longitudinal frame members 53. The whole truck frame is protected with a covering of refractory material 54 which may be concrete including fire clay.

10 As shown in Figs. V and VI, said roller shafts 34 and 35 of the respective rollers 29 and 30 are each journaled in four roller bearings 56, two of which are mounted upon the truck frame members 51 and two of 15 which are mounted upon the truck frame members 53.

As shown in Figs. VII and VIII; said bearings 56 are provided with passageways 57 for water or other refrigerant which 20 is circulated through said passageways, through pipes 58. As indicated in Fig. VIII; said passageways 57 are conveniently formed by drilling two holes in such angular relation that they connect at their inner 25 ends. As indicated in Fig. VII; I find it convenient to form said shafts 34 and 35 each of two oppositely counterpart sections which are held together in the hubs of the worm gears 36 by bolts 60 and are rigidly 30 connected with said gears by keys 61, as best shown at the left hand side of Fig. VI.

As indicated in Figs. III, V, and VI; I prefer to provide each of said shafts 34 and 35 and the gears and bearings there- 35 of with housings which include two arched castings 62, which are coupled by arch castings 63, as best shown in Fig. V. Moreover, I find it convenient to provide said worm shaft 38 with roller bearings 65 supported 40 by said truck frames 53 as indicated in Fig. VI. Referring to Fig. III; it may be observed that the construction and arrangement of said gear 45 which is carried by said truck, and the motor pinion 46 which is 45 ordinarily meshed therewith, is such that said truck may be withdrawn from operative engagement with the motor without removing said motor pinion 46.

As indicated in Figs. IV and V; said truck frames 51 carry sealing flanges 67 which slide in said sealing grooves 5 in a mobile sealing material 68, which may be sand or any other material suitable for preventing a draft between the truck frame 55 and the furnace foundation 6 so as not to disturb the course of the products of combustion above described and attain the maximum heating efficiency thereof with respect to the pipes 24. However, although such details of construction are of practical importance in the embodiment of my invention chosen for illustration, they are not essential to the operation of the rollers 29 and 30 as above described.

60 For the purpose of annealing cast iron

pipes, I prefer to maintain the confined atmosphere in said furnace at a temperature above 1400° F., at the region of introduction of said pipes 24, and to introduce the latter while the pipe is at a temperature 70 above 1000° F., and to progress the pipes through said furnace at such a rate that they are cooled to less than 500° F., before withdrawing them from said secluded atmosphere into the open atmosphere. However, such temperatures of introduction, annealing and withdrawal may be varied in accordance with the nature of the metal 75 being cast.

Therefore, I do not desire to limit myself 80 to the precise details of construction and arrangement herein set forth, as it is obvious that various modifications may be made therein without departing from the essential features of my invention, as defined in 85 the appended claims.

I claim:

1. In an annealing furnace; the combination with an inclosure; of means arranged to maintain a confined atmosphere therein 90 at suitable temperatures, at one region, means arranged to rotate a pipe upon its own axis and intermittently progress the latter, transversely, into regions of successively lower temperature, in such atmosphere, including series of overlapped rollers 95 with their axes parallel with said pipe axis; each roller having a major sector concentric with its axis; and a minor sector which is recessed to form a crest, at one side of said 100 recess; means arranged to simultaneously rotate said rollers in either direction, including shafts coupling said rollers in pairs, respective worm gears on said shafts, worms 105 respectively engaging said gears, a worm shaft common to said worms, a worm gear on said worm shaft, a worm engaging the latter gear, a driving shaft transverse to said common shaft and carrying the latter worm, a gear on said driving shaft, and a 110 motor pinion engaging said gear; a truck carrying said rollers and their apertures, and having supporting wheels; and tracks for said truck wheels, whereby said rollers may be shifted in and out of said 115 furnace, on said truck.

2. In an annealing furnace; the combination with an inclosure; of means arranged to maintain a confined atmosphere therein at suitable temperatures, at one region, means 120 arranged to rotate a pipe upon its own axis and intermittently progress the latter, transversely, into regions of successively lower temperature, in such atmosphere, including series of overlapped rollers with their 125 axes parallel with said pipe axis; each roller having a major sector concentric with its axis, and a minor sector which is recessed to form a crest, at one side of said recess; means arranged to simultaneously rotate 130

said rollers in either direction, including shafts coupling said rollers in pairs; a truck carrying said rollers and their appurtenances, and having supporting wheels; and 5 tracks for said truck wheels, whereby said rollers may be shifted in and out of said furnace, on said truck.

3. In an annealing furnace; the combination with an inclosure; of means arranged 10 to maintain a confined atmosphere therein at suitable temperatures; means arranged to rotate a pipe upon its own axis and intermittently progress the latter, transversely, into regions of successively lower temperature, in such atmosphere, until said pipe has 15 cooled; including series of overlapped rollers with their axes parallel with said pipe axis; each roller having a major sector concentric with its axis, and a minor sector 20 which is recessed to form a crest, at one side of said recess; means arranged to simultaneously rotate said rollers in either direction, including shafts coupling said rollers in pairs, respective worm gears on said 25 shafts, worms respectively engaging said gears, a worm shaft common to said worms, a worm gear on said worm shaft, a worm engaging the latter gear, a driving shaft transverse to said common shaft and carrying 30 the latter worm, a gear on said driving shaft, and a motor pinion engaging said gear.

4. In an annealing furnace; the combination with an inclosure; of means arranged 35 to maintain a confined atmosphere therein at suitable temperatures; means arranged to rotate a pipe upon its own axis and intermittently progress the latter, transversely, into regions of successively lower temperature, in such atmosphere, until said pipe 40 has cooled; including series of rollers with their axes parallel with said pipe axis; each roller having a major sector concentric with its axis, and a minor sector which is recessed 45 to form a crest, at one side of said recess; and means arranged to simultaneously rotate said rollers in either direction, including shafts coupling said rollers in pairs.

5. In an annealing furnace; the combination with an inclosure; of means arranged 50 to maintain a confined atmosphere therein at suitable temperatures; means arranged to rotate a pipe upon its own axis and intermittently progress the latter, transversely, into regions of successively lower temperature, in such atmosphere, until said pipe has 55 cooled; including series of rollers with their axes parallel with said pipe axis; each roller having a sector concentric with its axis, and 60 a sector which is recessed; and means arranged to simultaneously rotate said rollers in either direction.

6. In an annealing furnace; the combination with an inclosure; of means arranged 65 to maintain a confined atmosphere therein at

suitable temperatures; means arranged to rotate a pipe upon its own axis and intermittently progress the latter, transversely, into regions of successively lower temperature, in such atmosphere, until said pipe has 70 cooled; including series of rollers with their axes parallel with said pipe axis; each roller having a sector concentric with its axis, and a sector which is recessed; and means arranged to simultaneously rotate said rollers. 75

7. In an annealing furnace; the combination with an inclosure; of means arranged to maintain an atmosphere therein at suitable temperatures; means arranged to rotate a pipe upon its own axis and intermittently progress the latter, transversely in said furnace; including rollers with their axes parallel with said pipe axis; each roller having at its circumference means arranged to engage and turn a pipe; means arranged 80 to simultaneously rotate said rollers; and a truck carrying said rollers and their appurtenances, and having supporting wheels; whereby said rollers may be shifted in and out of said furnace, on said truck. 90

8. In an annealing furnace; the combination with an inclosure; of means arranged to maintain an atmosphere therein at suitable temperatures; means arranged to rotate a pipe upon its own axis and intermittently progress the latter, transversely, in said furnace; including rollers with their axes parallel with said pipe axis, each roller having at its circumference means arranged to engage and turn a pipe, and means arranged 95 to simultaneously rotate said rollers. 100

9. A pipe annealing furnace having a long furnace chamber with a bottom formed with a longitudinally extending opening in combination with a carriage movable into and out of said opening, and substantially of the same length as the furnace, refractory material supported on said carriage and forming, when the carriage is in place, a central section of the furnace bottom spaced 105 from the fixed section by longitudinally extending spaces, a series of transversely extending parallel shafts supported on the carriage and extending into the longitudinal spaces at the sides thereof, pipe supporting 110 rollers secured to the ends of the shafts and extending above the furnace bottom and means for simultaneously driving the shafts and rollers supported on the carriage below the refractory material carried thereby. 115

10. A pipe annealing furnace having a long furnace chamber with a bottom formed with a longitudinally extending opening in combination with a carriage movable into and out of said opening, and substantially of the same length as the furnace, refractory material supported on said carriage and forming, when the carriage is in place, a central section of the furnace bottom spaced 125 from the fixed section by longitudinally extending spaces, a series of transversely extending parallel shafts supported on the carriage below the refractory material carried thereby. 130

- tending spaces, means for forming a seal between the sides of the carriage and the opening in the furnace bottom at the bottom of the longitudinal spaces, a series of transversely extending parallel shafts supported on the carriage and extending into the longitudinal spaces at the sides thereof, pipe supporting rollers secured to the ends of the shafts and extending above the furnace bottom and means for simultaneously driving the shafts and rollers supported on the carriage below the refractory material carried thereby.
11. A pipe annealing furnace having a long furnace chamber with a bottom formed with a longitudinally extending opening in combination with a carriage movable into and out of said opening, and substantially of the same length as the furnace, refractory material supported on said carriage and forming, when the carriage is in place, a central section of the furnace bottom spaced from the fixed section by longitudinally extending spaces, and forming also protecting walls for the sides of the carriage, a series of transversely extending parallel shafts supported on the carriage and extending into the longitudinal spaces at the sides thereof, pipe supporting rollers secured to the ends of the shafts and extending above the furnace bottom and means for simultaneously driving the shafts and rollers supported on the carriage below the refractory material carried thereby.
12. A carriage adapted for use in connection with a pipe annealing furnace, said carriage having a steel frame, a multiple series of parallel sets of aligned water cooled bearings supported on said frame, a multiple series of parallel shafts supported in said bearings and extending beyond the sides of the carriage, means for simultaneously driving said shafts, pipe supporting rollers supported on the ends of the shafts, and refractory material supported on the carriage frame and protecting the top and sides of the frame from the heat of the furnace.
13. A carriage adapted for use in connection with a pipe annealing furnace, said carriage comprising a steel frame, a multiple series of aligned sets of water cooled bearings supported on the frame, a multiple series of parallel shafts supported on the bearings and extending beyond the sides of the carriage, pipe supporting rollers secured to the ends of the shafts, means for simultaneously rotating the shafts and rollers, a series of parallel metal arches supported on the top of the carriage frame and forming housings for the shafts and bearings and refractory material supported on said arches and on the sides of the carriage to protect the same from the heat of the furnace.
14. A carriage adapted for use in connection with a pipe annealing furnace comprising a steel frame, a series of parallel shafts extending beyond the sides of the frame, pipe supporting rollers secured to the ends of said shafts and alternately overlapping each other so as to form a series of pipe supporting bights, said rollers having recesses formed in their pipe supporting faces to receive and shift the pipes from one to a succeeding bight, means for simultaneously rotating the shafts and rollers and refractory material supported on the top and sides of the frame to protect the shaft bearings and actuating mechanism from the heat of the furnace.
- In testimony whereof, I have hereunto signed my name at Philadelphia, Pennsylvania, this twenty-fourth day of April, 1923.
- THOMAS PEACOCK ANTHONY.
